CLAIM

The ornamental design for a bottle holder, as shown and described.

DESCRIPTION

FIG. 1 is a front, top perspective view of a bottle holder; FIG. 2 is a rear, bottom perspective view of the bottle holder of FIG. 1;

FIG. 3 is a front plan view of the bottle holder of FIG. 1; FIG. 4 is a rear plan view of the bottle holder of FIG. 1; FIG. 5 is a left side view of the bottle holder of FIG. 1; FIG. 6 is a right side view of the bottle holder of FIG. 1; FIG. 7 is a bottom plan view of the bottle holder of FIG. 1; FIG. 8 is a top plan view of the bottle holder of FIG. 1; FIG. 9 is a front, top perspective view of the bottle holder of FIG. 1, wherein a top portion thereof is in an open position; and,

FIG. 10 is a rear, bottom perspective view of the bottle holder of FIG. 1, wherein the top portion thereof is in the open position.

The broken lines shown in the drawings depict portions of the bottle holder that form no part of the claimed design.
